U.S. Cl. D90—15

FIG. 1 is a perspective view of a decorative seat brace showing my new design.

FIG. 2 is a fragmentary front elevational view of the ornamental seat brace of FIG. 1.

FIG. 3 is a side elevational view thereof as viewed from one side. The side elevational view from the opposite side from that shown in FIG. 3 is a mirror image thereof.

FIG. 4 is a modified embodiment of my design and is a view similar to FIG. 2. The modified design of FIG. 4 is the same in all respects to the design of FIGS. 1, 2 and 3 except that the facial features and simulated hair are omitted from the cover of the design of FIG. 4. The cover of the modified design of FIG. 4 is plain and has the same appearance on the opposite side from that shown in FIG. 4.

The bicycle shown in broken lines in FIGURE 1 is included for illustrative purposes only.

I claim:

The ornamental design for a decorative seat brace, as shown and described.
